The ornamental design for a crash cart, as shown and described.

DESCRIPTION

FIG. 1 is a perspective view of a crash cart in accordance with the design;

FIG. 2 is a front view of the crash cart in accordance with the design;

FIG. 3 is a rear view of the crash cart in accordance with the design;

FIG. 4 is a first side view of the crash cart in accordance with the design;

FIG. 5 is a second side view of the crash cart in accordance with the design; and,

FIG. 6 is a top plan view of the crash cart in accordance with the design.

In the drawings, the broken lines are for the purpose of illustrating portions of the crash cart that forms no part of the claimed design.
